DEFENSIVE PUBLICATION

UNITED STATES PATENT OFFICE

Published at the request of the applicant or owner in accordance with the Notice of Apr. 11, 1968, 849 O.G. 1221. Identification is by serial number of the application and the heading indicates the number of pages of specification, including claims, and of sheets of drawing contained in the application as originally filed. The file of this application is available to the public for inspection; reproduction may be purchased for 30 cents per sheet.

Applications published under the Defensive Publication Program have not been examined as to the merits of alleged invention. The Patent Office makes no assertion as to the novelty of the disclosed subject matter.

U.S. Cl. 252—121

No Drawing. 9 Pages Specification

Water-soluble phenolsulfonates are effective fillers for toilet bars containing natural and synthetic anionic detergents. As a filler they have improved compatibility with the anionic detergent and other ingredients of a commercial bar without diminishing the characteristic lather and feel. The phenolsulfonates in the form of their alkali metal or ammonium salts may be used as fillers for toilet bars containing such anionic detergents as: fatty acid soaps, C₈—C₂₂ alkyl sulfates, C₈—C₁₆ alkylbenzene sulfonates, sulfonates of alkylphenol-ethylene oxide condensates, fatty acid esters of N-methyl taurine, acyl isethionates and alkyl glyceral ether sulfonates.
